(57) **CLAIM**

The ornamental design for a handle as shown and described.

DESCRIPTION

FIG. 1 is a perspective view of a handle showing the new design, shown with environment;

FIG. 2 is a front elevational view of the handle of FIG. 1, the rear elevational view being a mirror image thereof;

FIG. 3 is a left side elevational view of the handle of FIG. 1;

FIG. 4 is a right side elevational view of the handle of FIG. 1;

FIG. 5 is a top plan view of the handle of FIG. 1; and,
FIG. 6 is a bottom plan view of the handle of FIG. 1.

The broken line showing of a handle is for the purpose of illustrating portions of the article and forms no part of the claimed design. The broken line showing of a faucet is for the purpose of illustrating environmental structure and forms no part of the claimed design.

1 Claim, 4 Drawing Sheets
